UNITED STATES PATENT OFFICE

WINIFRED C. HEITMEYER, OF APPLETON, WISCONSIN, ASSIGNEE, BY MESNE ASSIGNMENTS, TO INTERNATIONAL CELLUCOTTON PRODUCTS COMPANY, OF CHICAGO, ILLINOIS, A CORPORATION OF DELAWARE

ABSORBENT PAD

Application filed December 10, 1929. Serial No. 412,974.

This invention relates to absorbent pads or bandages in general, although having more particular reference to sanitary napkins.

The main objects of the invention are to provide means in an absorbent pad whereby substantially the entire area thereof is caused to absorb fluid even though the fluid be applied to the pad at a localized point; to provide an elongated absorbent pad structure wherein the area of absorption is spread longitudinally of the pad from any locus of application of the absorbed fluid; to provide an absorbent pad of the character described which is readily disintegrable in water; to provide means which tend to spread the area of absorption interiorly of the pad, thereby tending to maintain the outer, top and bottom surfaces of the pad comparatively dry; to provide an absorbent pad, mainly of the sanitary napkin type, having means tending to prevent absorption from spreading to the side edge portions of the pad, or in other words, tending to maintain said side edge portions dry; to provide a pad structure having the above described characteristics which can be cheaply and economically manufactured by automatic machinery; and in general, it is the object of my invention to provide an improved absorbent pad of the type referred to.

Other objects and advantages of my invention will be understood by reference to the following specification and accompanying drawing in which I have illustrated an absorbent pad of the sanitary napkin type in which a selected embodiment of my invention is incorporated.

In the drawing:

Fig. 1 is a plan, certain parts being broken away to more clearly show the interior structure.

Fig. 2 is a perspective of a section of the means provided for controlling or directing the spreading of the area of absorption, and

Fig. 3 is a section on the line 3—3 of Fig. 1.

Referring now to the drawing, my improved absorbent pad comprises an absorbent pad body 5 which is enclosed in a gauze or similar textile wrapper 6.

The pad body 5 is preferably formed of a

suitable absorbent wood pulp product such as crepe paper, a plurality of plies or layers of crepe paper being superposed, one over the other, to provide the desired pad thickness. The direction of creping in the paper sheets is preferably arranged to run longitudinally of the pad body which is more or less elongated as clearly shown in Fig. 1, it being desirable to thus arrange the creping since innumerable small passageways or interspaces are formed between the adjacent plies of crepe paper, these passageways, constituting in effect, capillary tubes and planes which naturally tend to spread longitudinally of the napkin, absorption of fluid which is applied thereto at any localized point.

To further facilitate the spreading of the area of absorption from any locus of application, I compress a plurality of the layers or plies of crepe paper, preferably an intermediate series of the layers as clearly shown at 7 in Fig. 3. This intermediate series of plies preferably is compressed over its entire area so that capillary tubes and planes are formed therebetween, whereby the said intermediate series of plies has, in its entirety, a normal tendency to spread or diffuse the area of absorption interiorly and longitudinally of the pad body faster than the area of diffusion would spread in the main pad body in the absence of such compressed layers. The said layers are further compressed to a higher degree along transversely spaced, longitudinally extending zones indicated at 8, thereby forming longitudinally extending, narrow zones having smaller tube formations which have a greater capillarity than the capillary tube formations in the balance of the compressed plies.

The intermediate series of layers 7 are thus provided with alternately arranged longitudinally extending zones of relatively high and low compression in which there is a differential capillary attraction. In other words, the zones of high compression will spread or conduct the absorbed fluid longitudinally of the pad faster than the elongated zones of lower compression. The zones of low compression will tend to draw fluid from the main pad body and to carry the

fluid away from the locus of application with greater rapidity than the surrounding portions of the pad proper. The said zones of low compression will also feed the fluid to the zones of high compression, which will obviously serve to even more quickly convey the fluid longitudinally of the pad, to portions of the main pad body which are comparatively dry, and which retain up to that time, a high degree of absorbency. The comparatively dry parts of the pad body then operate to absorb the fluid from the intermediate compressed, absorption spreading layers.

15 The action of the narrow zones which accelerate the spread of the area of absorption longitudinally of the pad may be likened to that of strips of blotting paper which has the capacity of quickly absorbing fluid from another paper and leading the absorbed fluid away from the locus of application. It may be observed that the spreading effect is due to a positive conveying or leading action by reason of the capillary effect provided, rather than by reason of a forcing or baffle effect such as found in sanitary napkin structures having an intermediate, more or less impervious layer to prevent absorption from passing entirely through the napkin from top to bottom.

As a practical matter, the intermediate compressed series of crepe paper sheets may be formed by passing a series of superposed sheets through suitable rollers having a rib-like structure which will serve to compress the sheets as desired. The sheets may be in the form of supply strips or rolls of any convenient width which may be subsequently fed between the desired layers of crepe paper also in the form of supply strips or rolls, to form the sandwich effect shown in Fig. 3, after which the sandwich structure may be divided into pads of the desired widths and lengths. Thus it will be apparent that the napkin structure may be cheaply and economically manufactured by comparatively simple automatic machinery.

The intermediate compressed layers of plies are preferably somewhat shorter than the length of the pad body as shown so that the ends of the pad proper are not called upon to absorb fluid from the said intermediate layers, whereby the pad ends are kept dry and are slight in bulk.

55 An absorbent pad structure such as above described is desirably made of a suitable wood pulp product such as, for instance, crepe paper because of the fact that such a product is readily disintegrable in water and can therefore be disposed of through ordinary toilet facilities without danger of clogging the same. Obviously, other materials may also be used and treated in the manner above described to secure the advantages of spreading the area of absorption so as to

utilize substantially the full or the desired length of the absorbent pad, and I am aware that other changes in the above described structure and arrangement may be made without departing from the spirit of my invention, the scope of which should therefore be determined by reference to the following claims, the same being construed as broadly as possible consistent with the state of the art.

75 I claim as my invention:

1. In an absorbent body, means for controlling the direction in which absorption spreads from the locus of application of the absorbed fluid, comprising a plurality of 80 co-planar parts in which the body is compressed so as to increase the capillarity of said parts relative to the capillarity of the balance of the body, said parts being elongated in the desired direction of spreading.

85 2. In a sanitary napkin, the combination of an absorptive pad member and a wrapper therefor of textile material said pad member comprising a plurality of superposed layers of crepe paper, a plurality of said layers being provided with transversely spaced, longitudinally extending areas in which said layers are compressed together, said compressed areas having a higher degree of capillarity than the intermediate, relatively 90 incompressed areas, and serving to accelerate the longitudinal spread of the area of absorption in said pad, from the point of application of the absorbed fluid.

95 3. In a sanitary napkin, the combination 100 of an absorptive pad member and a wrapper therefor of textile material, said pad member comprising a plurality of superposed layers of crepe paper, an intermediate series of said layers being provided with transversely 105 spaced, longitudinally extending areas in which said layers are compressed together, said compressed areas having a higher degree of capillarity than the intermediate incompressed areas, and serving to accelerate 110 the longitudinal spread of the area of absorption in said pad from the point of application of the absorbed fluid.

115 4. A pad body for a sanitary napkin comprising a plurality of superposed layers 120 of crepe paper, a plurality of said superposed layers being more highly compressed together than the other layers, and said compressed series of intermediate layers being also provided with a plurality of transversely 125 spaced, longitudinally extending areas in which said layers are further compressed so as to form in said compressed series of layers, a plurality of alternately arranged, longitudinally extending areas in which there is 130 a differential capillary attraction, the areas of greatest attraction serving to accelerate the spread of the area of absorption longitudinally of the pad from the locus of application of the absorbed fluid.

5. A device as defined in claim 3, wherein
said intermediate series of layers terminate
short of the ends of the outer layers.

6. A device as defined in claim 4, wherein
5 said intermediate series of layers terminate
short of the ends of the outer layers.

7. A sanitary napkin which includes an
elongated absorbent filler pad composed of
fibrous absorbent material and which in-
10 cludes a plurality of co-planar interior spaced
parts extending longitudinally of the elon-
gated pad, said parts being relatively more
compact than the remainder of the filler
15 whereby fluid absorbed by the pad is caused
to flow longitudinally of the pad from the
point of application of fluid at an accelerated
rate relative to flow in other directions in
the pad.
